CONSTRUCTION FOR SLEEVED GARMENT

Harry S. Geiss, New York, N. Y.

Application March 16, 1956, Serial No. 571,959

1 Claim. (Cl. 2—125)

My invention relates to improvements in sleeved garments and more particularly to a garment construction in which the sleeve is attached to the body of the garment in such a way as to permit unrestricted relative movement of the arms and body of the wearer without appreciable pull on either the body or sleeve of the garment. The invention is applicable to various types of garments for either sport or regular wear, including shirts, pajamas, jackets, blouses, dresses and other sleeved garments.

Various proposals have been made for providing free arm movement in garment structures, but for the most part, these proposals relate to the provision of an insert or gusset at the armpit of the garment intended to give increased freedom of movement over sleeved garments constructed in the ordinary manner. Such proposals are illustrated, for example, by the disclosure of the patent to Lee No. 2,314,226.

While the prior proposals may provide some arm freedom with underarm inserts, as far as known, the sleeves are attached directly to the body of the garment over all of the perimeter of the armhole of the garment, except for the underarm portion where the insert is provided. Therefore, in at least some cases, an added strain is created along the joint or seam between the sleeve proper and the body portion of the garment in which the armhole is provided. This is particularly true in the areas adjacent the points where the sleeve proper is attached directly to the body of the garment at the edge of the insert.

The primary object, therefore, of my invention is to provide a sleeved garment construction in which there is unlimited freedom of movement between the sleeve and the body of the garment.

A further object of the invention is to provide a sleeved garment construction which avoids the difficulties encountered in connection with previous proposals and which contains no point of stress between the sleeve and the body of the garment.

Accordingly, my invention comprises in general a sleeved garment structure in which the sleeves and body of the garment are joined together by a coupling band of fabric stretchable in all directions. This coupling band is advantageously a specially woven knitted type fabric adapted to stretch in any direction in response to a substantially effortless pull in that direction and to recover its normal condition when free of any unequally applied stress or pull.

In a preferred construction the coupling band has a substantially uniform width along the front, top and back of the armhole or sleeve attachment section of the garment and advantageously includes two elongated substantially V-shaped or U-shaped sections respectively projecting from its inner and outer edges adapted to be secured respectively in the armpit section of the sleeve and body of the garment provided with correspondingly shaped underarm openings or cut-outs. The coupling

2

band may include either one or both of the projecting sections.

A sleeved garment including the stretchable coupling fabric, joining the sleeve and body of the garment, permits unrestricted movement of the wearer's arms in any direction without applying any stress whatever to the wearer or to the body or sleeve of the garment. The coupling band gives freedom all around the shoulder. At the top, for example, there is no down-pull on the yoke when the wearer reaches down, as in bowling. Furthermore, the garment will not ride up or pull out of skirts, slacks or trousers, when arms are raised. This type of construction is particularly important for garments used in many sports and in many occupations.

15 The improved garment construction of the present invention includes other features and advantages described more in detail hereinafter in connection with the accompanying drawings illustrating one embodiment of the invention and forming a part of this application.

20 In the drawings:

Fig. 1 is a broken view, partly in section and partly to one side, of a shirt constructed in accordance with the invention illustrating the relationship between the sleeve, fabric coupling ring and body portion of the shirt;

25 Fig. 2 is an enlarged broken sectional view taken on the line 2—2 of Fig. 1;

Fig. 3 is an enlarged broken elevational view looking toward the underarm portion of the shirt of Fig. 1 from the side, showing the coupling fabric stretched vertically;

30 Fig. 4 is a view similar to that of Fig. 3 showing the coupling fabric expanded or stretched laterally; and

Fig. 5 is an enlarged detailed view of the fabric coupling ring shown in Fig. 1 looking toward the edge to be stitched to the attachment edge or edges of the sleeve.

Referring to Fig. 1 of the drawing, the shirt shown therein is constructed of suitable shirting material, such as broadcloth, and is made substantially on a standard shirt pattern, except for the armhole or shoulder structure. The shirt, as shown, comprises front sections 10 attached respectively to opposite sides of a back section 12 by underarm seams, one of which is shown at 14, and by the usual shoulder seams, and yoke 15. The shirt may or may not have the pocket illustrated and may 45 have a collar of different style than that shown, or have no collar at all. The shirt shown in Fig. 1 includes one-piece sleeves 16 (only one being shown), having an underarm seam 18, the upper portion only of which is shown in the drawings. The sleeve 16 may be two-piece or

50 more. The sleeve 16 is joined to the body of the garment by means of a coupling member 20 of a fabric adapted to stretch in all directions and shown in Fig. 1 in substantially unstretched condition. The coupling member 20 is generally ring shaped, as shown in Fig. 5, the opposite edges 22 and 24 of which are respectively attached to the attachment edge or edges of the sleeve 16 and to the attachment edge or edges of the armhole provided by the front and back sections 10 and 12 and the yoke 15 of the shirt. These attachments are 55 formed respectively by seams 26 and 28.

The body of the shirt as shown in Fig. 1 is provided with a V-shaped armpit cut-out extending substantially below the underarm portion of the shirt and terminating at the upper end of the seam 14. The sleeve includes 60 a similar cut-out in the underarm portion extending to the inner end of the seam 18. In a similar manner the fabric coupling member 20 includes generally V-shaped oppositely-arranged extensions or tabs 30 and 31 extending respectively into and fitting in the V-shaped cut-outs or openings in the body and sleeve of the garment. The extension or projecting section 30 is attached to the front and back sections 10 and 12 by seams 32 and 33,

which extend from the upper end of the seam 14 and merge into and comprise portions of the seam 28. The projecting section 31, substantially opposite the section 30 is attached in the cut-out of the underarm portion of the sleeve 16 by seams 34 and 35, which continue from seam 18 and merge into and comprise portions of seam 26. The extensions 30 and 31 may have a rounded or square (U) shaped lower end fitting in a corresponding cut-out.

In constructions in which the generally ring-shaped coupling member is not provided with an extension 30 or 31, the ring member may have substantially the same width throughout, and the seams 26 and 28 may be continuous arcuate seams. The appearance at the back of the garment is generally the same as that of the front.

Fig. 3 of the drawings shows the coupling member 20 with its extensions 30 and 31 in somewhat vertically elongated position, while Fig. 4 shows the section 30 of the coupling member in extended or stretched position, as a result of tension applied to the body portions 10 and 12 in the direction of the arrows 36 and 38. Double-headed arrows 40 and 42 are applied over the fabric of the coupling member in Figs. 3 and 4 to indicate that the material is stretchable in all directions and adapted to recover to its normal unstretched condition.

Fig. 5 illustrates the fact that the fabric coupling member forms a complete ring at the armpit or shoulder section of the garment. Fig. 5 shows the coupling member before being sewn into the shirt, but in a shape generally approximating that assumed when the shirt is being worn with the possible exception of the section 31, shown extending into the ring. The coupling members 20 are not only completely ring-shaped so as to form a complete coupling between the sleeves and body of the garment but are preferably provided with no cross seams so that the material is able to stretch at all points in any direction. As a consequence of this the coupling members are preferably cut from tubular woven knitted type stock so that, before these members are sewn into a shirt or other garment, they are cylindrical, as the coupling member 20 appears in Fig. 1, with the exception of the extension 30, which is bent downwardly. In this view the extension 31 extends out from the body of the member 20 almost as a straight continuation. Where the coupling members 20 are of uniform width and cylindrical, the seams 26 and 28 are of substantially the same length, and they may be the same length in Fig. 1, with the exception of the seam extensions 32 to 34 used in securing the projecting sections 30 and 31, which project from the ring or body section of the coupling members 20.

The coupling members for securing the sleeves to the body of the garment may be made of any elastic material stretchable in all directions, without the application of appreciable stress, but is preferably a knitted fab-

ric material made with an elastic weave, such as the weave or fabric known as "Helanca." Other similar weaves or fabrics may be used which are suitable for the purpose as specified herein. Furthermore, the coupling members, 5 such as 20, may be the same color as the body of the shirt or other garment, or may comprise material of a contrasting or harmonizing color. In certain types of sports clothes, the coupling member may be used to provide for the desired freedom of movement and also be utilized as a decorative feature. Therefore, the edges of the member 20 and the edges of the sleeve and garment to which they are sewn may be shaped other than straight so long as a substantial width of elastic fabric, for example from $\frac{3}{4}$ to $1\frac{1}{2}$ inches in width, is provided to give the desired freedom of movement between the sleeve and body of the garment, while being worn.

What I claim is:

A garment comprising a body portion, a sleeve having an attachment end and having in the armpit section upwardly diverging edges forming a V-shaped cut-out terminating at its attachment end, the body portion including a relatively non-stretchable material defining a shoulder and armhole structure, the front and back sections of the garment, being cut along downwardly converging lines to form a V-shaped cut-out in the armhole structure at the armpit, and a coupling member stretchable in all directions in the form of a ring, said coupling member having integral oppositely projecting V-shaped projections of substantially the same shape and size as the V-shaped cut-outs in the sleeve and body portion, respectively, the edges of said projections merging with the respective edges of the ring along smoothly converging lines, the opposite sides of the coupling member being secured, respectively, to the attachment edge of the sleeve and the armhole section of the body portion, the edges of the V-shaped sections being secured to the edges of the cut-out sections in the sleeve and body portion, respectively, portions of the ring and portions of the projections at the armpit section extending into the front and back sections of the garment, the coupling member permitting unrestricted movement between the sleeve and body of the garment and freedom of movement of the shoulders of the wearer.
